UNITED STATES PATENT OFFICE.

CHARLES H. MCCLINTOCK, OF HARTFORD CITY, INDIANA.

CRUDE-OIL ENGINE.

No. 879,884.

Specification of Letters Patent.

Patented Feb. 25, 1908.

Application filed December 24, 1906. Serial No. 349,238.

To all whom it may concern:

Be it known that I, CHARLES H. MCCLINTOCK, a citizen of the United States, residing at Hartford City, in the county of Blackford 5 and State of Indiana, have invented a new and useful Crude-Oil Engine, of which the following is a specification.

My invention has reference to improvements in internal combustion engines of the 10 class wherein the fluid admixture of the hydrocarbons of crude oil, and air, is introduced into the mixing chamber by the suction produced by the stroke of the engine's piston, and has for its objects to provide an engine 15 which will be simple and compact in construction, of few parts, and which may be operated easily and economically, and which will not be liable to get out of order or adjustment.

20 The features of my invention consist of the novel arrangement and construction of the feeding mechanism so that it may be automatically operated by the speed-governor, whereby the feeding of the oil and the air 25 which together constitute the fuel for the operation of the engine, is accomplished in an improved manner, and whereby the amount of fuel consumed by the engine will be varied proportionately to the varying degree of power developed by the engine, and 30 further, whereby the mechanism may be adjusted to work successfully with oils of varying density.

The objects above stated and other purposes which will become apparent as the 35 specification of my invention is disclosed, are accomplished by the novel and new construction, combination and arrangement of parts and mechanism described in this specification, illustrated in the accompanying drawings, 40 and designated in the appended claims.

In the drawings—Figure 1 is a side view of my improved engine, one of the fly-wheels and one of the side-caps of the frame being 45 removed. Fig. 2 is a top plan view of my improved engine, a portion of the top-cap of the frame having been broken away. Fig. 3 represents a vertical central longitudinal section of my improved engine, and Fig. 4 is an 50 end view of the same, the cylinder head having been removed. Fig. 5 is a detached view of the feed-chest seat and the feed-ports. Fig. 6 is a transverse sectional view of the frame taken on the line 6—6 Fig. 1,

the feeding-mechanism being removed. Fig. 55 7 is a detached enlarged side view, and Fig. 8 is a like transverse sectional view of the side-cap. Fig. 9 is a detached enlarged end view and Fig. 10 a longitudinal sectional view of the piston. Fig. 11 is a detached enlarged 60 central longitudinal view, and Fig. 12 is a detached enlarged transverse central sectional view of the feeding mechanism. Fig. 13 is a detailed enlarged view of the removable 65 main-journal box.

Similar characters of reference refer to corresponding parts throughout the several views.

The frame and body of my improved engine is of the simple construction and arrangement as plainly shown in the several views, and is so designed as to be cast in a single piece for engines of the smaller sizes. In the larger sizes the cylinder is cast separately and joined to the main portion of the 70 frame in a suitable manner. In this specification of my invention I have shown the same embodied in the form of construction and details of the smaller sized engine illustrated in the drawings.

The smoothly bored cylinder 1 communicates with the chamber 2; leading from this chamber is the channel 3 which terminates in the mouth 4 enlarged into the form as shown in Fig. 3 and Fig. 5, and about which 75 mouth is provided the machined seat 5 upon which is secured the feeding mechanism to be hereinafter described.

6 designates the feed ports leading from the mouth 4 into the cylinder, and 7 are the 80 exhaust ports which are of increased dimension and which form ample communication from the cylinder into the exhaust chamber and pipe 8 through which the spent products of combustion are conveyed into a proper 85 receptacle or discharged into the air.

9 designates a cavity extending continuously about the cylinder bore; at the ends of the cylinder the webs 10 are provided, as shown in Fig. 4, to receive the bolts securing the cylinder-head in position. The cylinder-head 11 is in like manner provided with a continuous cavity therein, broken only by the suitable webs provided in its 100 face for the reception of the securing bolts, and corresponding with the like webs in the cylinder. As plainly shown, the cavity 9 105 communicates freely with the cavity of the

cylinder-head so that the free circulation of the water about the cylinder and the cylinder-head is effected, its introduction being had at the pipe 12 and its escape at the pipe 13. The cylinder and its head may thus be kept free from undue heating while the engine is in operation.

The forward top and end of the frame are finished so as to receive the top-cap 14 and the end-cap 15 which are bolted thereon, a suitable layer of packing being interposed so that these openings of the chamber 2 are sealed. The side walls of the chamber are provided with the vertically disposed integrally formed housing walls 16, as shown in Fig. 1, the bottom of the housing being formed on an oblique angle wherein the lower boxings for the bearing of the main-shaft 17 are retained.

18 designates the upper box which fits snugly and slidably in the housings 16 and is retained in true position against the shaft by the set screw 19.

20 designates the side caps, a detail thereof being shown at Fig. 7 and Fig. 8, which are adapted to be bolted tightly on the housing faces, a layer of suitable packing being interposed so as to make a sealed joint. These side caps are provided with the thickened portion 21 transversely perforated for the reception of the shaft 17 and having stuffing boxes 22 therein so that the opening of the chamber-wall through which the shaft passes, may be packed, thereby preventing the escape about the shaft of the contents of the chamber the reasons whereof will be presently disclosed. This improved construction of the frame and casing is more fully specified and particularly claimed in my divisional application, Serial No. 375819 filed May, 27, 1907.

The piston 23 is of the structure and conformation as plainly shown in Fig. 2, and in detail in Fig. 9 and Fig. 10, and is composed of a hollow member, closed at its one end and machined on its exterior to nicely fit the bore of the cylinder. The well known split-ring packing is used. The closed end of the piston is provided with the deflector 24 positioned toward the edge of the piston nearest the feed port, and of the form as shown in Fig. 3 and Figs. 9 and 10, the function of which deflector will be presently disclosed. This piston is provided with suitable bearing upon which is pivotally retained one end of the pitman 25, its opposite end being pivotally secured to the wrist of the double crank of the shaft 17, upon the extending portions of which shaft are the fly wheels.

60 The lower part of the frame or body of the engine is hollowed out as shown in Fig. 3 so that unnecessary weight is dispensed with.

The important feature of my invention is the feeding mechanism through which is in-

roduced the fuel with which the engine is operated. Of this mechanism 26 designates the feed-chest suitably flanged so as to be bolted on the seat 5 and having integrally formed arms 27 and 28 supporting the journal boxes 29 and 30, as shown in Fig. 12 in detail. These two journal boxes are sustained on a common plane and journaled in the box 30 is the shaft 31 with the pulley 32 rigidly secured thereto and belted to the main-shaft 17. The interior end of this shaft is enlarged into the sleeve 33 having integrally formed lugs wherein are pivoted the centrifugal levers 34 weighted by the balls 35. Loosely retained in the bore of this sleeve is the head 36 having its end bifurcated for the reception, loosely, of the ends of the levers 34; the opposite end of this head 36 has a suitable bore wherein is journaled the shaft 37 the end of the bore and shaft being provided with the ball bearing 38 whereby such friction as may occur by the impingement of the sleeve against the end of the shaft 37 is minimized. The shaft 37 is journaled at its opposite end in the threaded bushing 39 retained in the box 29. This bushing is thus adjustable in position and may be locked in desired positions by the lock-nut 40 provided thereat.

41 designates the regulator-head secured detachably to the shaft 37, and provided with the oppositely disposed cams 42 and 43, as shown by the dotted lines in Fig. 2, the functions whereof will be hereinafter mentioned.

44 designates a coil-spring, its one end bearing against the regulator-head and its opposite end residing in the bore of the journal box 29 and against the bushing 39, the function of this spring is to firmly retain the shaft 37 in normal position in the sleeve 33. By the adjustable bushing the tension under which the centrifugal levers work may be easily regulated, as will be hereinafter referred to.

The feed-chest, as shown in Figs. 11 and 12, has the aperture 45 adapted to communicate freely with the throat 4, its lower edges being beveled and machined so as to receive the correspondingly beveled and finished edge of the valve 46 its upwardly disposed stem 47 being slidably retained in the suitable hole provided in the top of the chest and enlarged into the recess 48. In this recess resides the coil-spring 49 which bears against the underside of the head 50 secured on the valve-stem, whereby the valve 46 is retained normally firmly against its seat.

Secured on the opposite sides of the feed-chest communicatingly with the aperture 45 are the oil-inlet member and the air-inlet member as plainly shown in Fig. 3 and in Fig. 11. These members are provided with suitable flanges so as to be bolted securely to

the finished sides of the feed-chest, a layer of packing 26^a being interposed to effect a tight joint.

The head 51 of the oil-inlet member is 5 suitably bored so as to retain slidingly the plunger 52, and the exterior end of the head is perforated by the small channel 53 where the pipe 54 leading from the oil supply is secured. This small channel 53 in turn 10 communicates with the enlarged oil-passage 55 which extends about the end of the plunger and opens below into the feed-chest. This plunger 52 is tapered on its end to fit in the cone-shaped enlargement of the channel 53. 15 The opposite end of the plunger has the shoulder 56 against which the end of the coil-spring 57, having its opposite end against the head 51, is impinged. The stem 58 is screwed into the end of the plunger 52 and 20 adapted to be adjustably retained therein by the lock-nut 59, is provided with the tip 60 adapted to fit movably and freely in the slot 42 of the regulator-head, as plainly shown in Figs. 2 and 11. Thus the plunger will be 25 retained with its tip normally in engagement with the slot 42 and the tapered end apart from the opening of the channel 53, and the width of this opening may be regulated to a nicety.

30 The head 61 of the oil-inlet member is hollowed out whereby the ample air-passage 62 is formed. The interior end of the head is bored so as to retain slidingly the plunger 63 and its opposite end is shouldered having 35 the face 66 threaded and has adjustably secured thereon the gage-cap 64. This cap has ample apertures 65^a therethrough so that free access of air into the air-inlet member is at all times afforded.

40 The plunger 63 is slidingly retained at its exterior end, in the suitable hole in the gage cap and has the valve 65 of smaller dimension than the bore of the cap secured thereto at such position with reference to the tip 67 45 that when the tip which is adapted to fit freely in the cam 43 occupies its normal position therein, the valve 65 will stand slightly away from the face 66. The coil-spring 68 about this plunger and having its ends bearing 50 against the gage-cap and the valve 65 performs the function of retaining the plunger tip pressed into its position against the cam 43.

From the foregoing disclosure of the construction and function of the various parts 55 of my invention, it will be easily understood that in the operation of the engine the amount of oil and the amount of air desired to be fed into the feed-chest may be regulated to answer any requirements and to the use of oils of varying density, and that as the desired speed of the engine is attained the feed of the oil and air in the proportions as fixed, will be lessened or increased, as the

performance of the engine is lesser or greater, 65 as the case may be.

69 designates the igniter, composed of a hollow member closed at its upper end, its lower end opening into the aperture communicating directly with the cylinder. This 70 igniter is kept heated sufficiently by any suitable means. I have used a gas flame introduced into and about the igniter and enclosed by the flue 70. A Bunsen burner or other means may be used as well whereby a 75 high and uniform degree of heat is maintained adjacent to and communicating with the igniter aperture of the cylinder. A suitable conduit is provided to convey the oil supply to the head 51, and is provided with 80 the suitable valve 72.

While I have shown my invention embodied in a machine of the construction described herein, and believe the best mode possible for the application of the principles 85 of the invention has been explained, it will be understood that minor changes may be made in the parts, and forms and details, which will not in the least affect the nature or principles of my invention. 90

When the engine is in readiness to operate, the top-cap, end-cap and side-caps all are secured in position and the packing about the main-shaft is effected, all of the working parts of the engine being closed in a substantially air-tight casement, and in the respective positions. The igniter is first properly brought to proper degree of heat. The valve 72 is opened permitting the oil to flow into the oil-inlet and feed-chest. As the piston is moved rearwardly a partial vacuum is produced in the chamber which causes the valve 46 to quickly open whereby a charge of oil and air which have been introduced through the feed-chest, is drawn forcibly 105 into the throat 4, this quick and forcible suction volatilizes the oil partially and draws it onward and into the chamber 2. Simultaneously with the movement of the piston forwardly, the valve 46 is closed and as the piston progresses and the pitman and crank agitate the contents of the chamber, the air and oil in the chamber and the channel are agitated violently, heated, and compressed. As the piston reaches the end of the forward 110 stroke the mixture is impelled through the feed ports and against the deflector on the piston. This sudden deflection of the mixture causes it to become further volatilized and vaporized; as the piston progresses rearwardly the charge of the volatilized and vaporized mixture in the cylinder is rapidly further vaporized by its increasing heat due to the compression of the same by the piston, and when the piston has reached the limit of 125 its rearward travel the mixture has become highly explosive and is instantly ignited by the heat maintained in the igniter aperture.

During the rearward movement of the piston, as just described, the valve 46 has been opened and a fresh charge of oil and air taken into the throat. By the force of the explosion, the piston is impelled forwardly with great power. As the piston reaches the limit of its forward stroke, and before the feed port has commenced to open, the exhaust port, so positioned and proportioned for the purpose, has been opened by the passing of the piston, and the spent products of combustion in the cylinder are expelled and all pressure in the cylinder disappears. As the piston again reaches the limit of its forward stroke the ports are again opened and a fresh charge of the volatilized oil enters through the feed port. Although the exhaust port is open during the time of the inlet of the volatilized mixture through the feed port, none of the mixture will escape from the cylinder as it is not at this time under pressure, and to prevent the possibility of any of the mixture escaping through the exhaust port by the impulse given it in its quick and forcible injection through the feed port the deflector is provided on the piston head which in addition to breaking and volatilizing the mixture striking it as heretofore referred to, performs the additional function of breaking the straight line of ingress, thereby preventing the escape of any portion of it through the exhaust-port. Immediately following the inlet of fresh mixture, as just described, the piston again moves forwardly and the operation as just described, is repeated. As the operation continues the walls of the frame and casement become warmed and the more rapidly the parts operate, the more perfectly the processes of volatilization, vaporization and combustion are accomplished. Complete lubrication of all of the working parts of the engine is also accomplished, and after the engine is started no further attention to it is necessary, other than occasionally the lubrication of the air plunger and the governor mechanism.

In the operation of my improved engine an exceedingly small quantity of oil is required. The consistency of the mixture of oil and air, as the same reaches the valve 46, may be regulated to a nicety by the manipulation of adjusting means of the oil plunger and the air plunger. After the plungers have been set as desired so that a certain feed of fuel for a given performance of the engine may be obtained, then the quota of the combined mixture proper to be fed into the chamber, is fixed by the adjustment of the spring-pressed regulator-head. The regulation of the speed of the engine is then automatically accomplished by the governor mechanism actuating the regulator-head whereby the feed of the mixed fuel is varied.

What I claim as my invention and desire to secure by Letters Patent is—

1. In a feeding mechanism for internal combustion engines, the combination of a feed-receptacle having a puppet-valve therein adapted to normally close the mouth of said feed-receptacle, an oil-inlet member and an air-inlet member leading into said feed-receptacle, a spring pressed valve in each of said members, the said valves having their stems disposed toward each other, a speed governor, and a device supported by said feed-receptacle and controlled by the said speed-governor and engaging said valve-stems to actuate the said valves simultaneously.

2. In a device of the kind described, the combination of a feed-receptacle having a puppet-valve therein adapted to normally close the mouth of said feed-receptacle, an oil-inlet member and an air-inlet member leading into said feed-receptacle each member having a spring-pressed valve therein, the stems of said valves being disposed toward each other, a speed-governor, means to actuate said valves including a wedge mounted between and in slidably engagement with the said valve-stems and adjustably secured on a shaft connected to the governor whereby the wedge will be moved by the action of the governor.

3. In a device of the kind described, the combination of a feed-receptacle having a puppet-valve therein adapted to normally close the mouth of said feed-receptacle, an oil-inlet member and an air-inlet member leading into said feed-receptacle each member having a spring-pressed valve therein, the stems of said valves being disposed toward each other, means to actuate said valves including a shaft having its one end journaled in a bearing supported by the feed-receptacle, its other end being journaled in the body-portion and engaging the arms of a centrifugal governor which is journaled on a bearing supported by the feed-receptacle, a wedge adjustably secured on said shaft and engaging the said valve-stems slidably but being not free to revolve, a spring to sustain the end of the shaft in actual engagement with the governor, and a device to adjust the tension of said spring, substantially as set forth.

4. In a device of the kind described, a feeding mechanism comprising a box-shaped receptacle with an aperture 45 having its lower inner edge machined to receive the face of the valve 46 positioned therein, its stem extending through the top of the receptacle, and having a head thereon and being sustained by a spring so that the valve is normally pressed against the seat of the aperture, oppositely disposed oil-inlet and air-in-

let members opening into the aperture, and having disposed slidingly in the heads thereof the adjustable valve stems 52 and 63 yeldingly pressed toward each other and 5 having valves thereon, a wedge between the stems of said valves mounted on the transversely extending shaft 37 which is slidingly supported at its one end in the journal-box 29 and yeldingly pressed by a spring against 10 the ball-bearing in the bifurcated head 36 journaled in the sleeve 33, this sleeve being

rotatably mounted in the journal-box 30 and having a pulley 32 thereon, and having pivotally supported on its sides weighted centrifugal levers, substantially as set forth. 15

In testimony whereof I have signed my name to this specification, in the presence of two subscribing witnesses.

CHARLES H. McCLINTOCK.
